UNITED STATES PATENT OFFICE.

AUGUST GROSS, OF NEW YORK, N. Y., ASSIGNOR TO MANHATTAN BRASS COMPANY, OF NEW YORK, N. Y., A CORPORATION OF NEW YORK.

COIN-RECEPTACLE.

SPECIFICATION forming part of Letters Patent No. 721,887, dated March 3, 1903.

Application filed December 22, 1902. Serial No. 136,161. (No model.)

To all whom it may concern:

Be it known that I, AUGUST GROSS, a citizen of the United States, residing in the borough of Bronx, city and State of New York, have 5 invented an Improvement in Coin-Receptacles, of which the following is a specification.

My invention relates to a coin-receptacle or money-bank of substantial character, construction, and strength, with the object of preventing the extraction of coin by and through the devices by which the coin is placed in the bank.

My invention consists in a plate fixed at one end to and within the coin-receptacle adjacent to the coin-slot and devices pivoted together and pivotally supported from said plate and substantially balanced in their movements and through which the coin is passed into the receptacle. This plate occupies an inclined position and at the free end is provided with a series of tongues and with trunnions at the sides, and I provide a chute having a bottom plate and sides turned up therefrom and pivotally supported from said 25 trunnions. This chute is provided with a turned-up end and a rib projecting through the coin-slot, at the other end with a series of tongues which interlock with the tongues of the fixed plate, and at the extreme inner 30 end of said chute a flap or shutter is pivoted to and between the sides of the chute. This flap or shutter hangs by gravity and normally covers the exit-opening between said plate and chute, permitting a coin to pass 35 into the receptacle, but preventing the coin being extracted therefrom.

In the drawings, Figure 1 is a vertical section at the line $z z$ of Fig. 2. Fig. 2 is a sectional plan at the line $x x$ of Fig. 1. Fig. 3 40 is a vertical section at the line $y y$ of Fig. 1 looking toward the left hand. Fig. 4 is a vertical section at the line $y y$ of Fig. 1 looking toward the right hand, and Fig. 5 is a vertical section at the corner of the coin-receptacle containing the features of my invention 45 and showing the parts in the position occupied thereby when the coin-box is turned upside down or inverted.

The coin receptacle or box is preferably 50 composed of strong metal plates, a representing the bottom plate, b the top plate, $c c'$ the

side plates, and $d d'$ the end plates. In the construction of the box or receptacle there are overlapping portions, which make it possible to securely rivet the parts together, and 55 a handle 2 is secured by straps to the top plate. The end d is provided with a door having a lock 3 for securing the same in position, said door swinging on the hinge-pin 4, and 5 is a coin-slot in the end d . The plate 60 e is of rectangular form, with one end bent at an obtuse angle, and this end is fixed by rivets 6 to the inner surface of the end d above the coin-slot, so that the plate e occupies an inclination, and the free end of this 65 plate is provided with a series of tongues e' , preferably inclined downward, and the sides of the plate are made with trunnions 7. A swinging chute f comprises a bottom plate and sides bent up at right angles thereto. 70 This chute is pivoted to trunnions 7 and is provided with an end rib 8, bent outward from the upturned end of the chute, the said rib 8 projecting through the coin-slot, and at the other end of said chute the bottom plate 75 is provided between the sides with a series of tongues f' , staggered in their relation to the tongues e' of the plate e , so that the tongues of the said series may interlock with one another. In this construction the fixed plate e 80 is between the sides of the chute. A flap or shutter g , having end trunnions 9, is pivoted to and between the sides of the chute, at the inner end thereof. The flap or shutter hangs by gravity, as the major portion of the same 85 is below the trunnions 9, and the only part projecting above the same is the central tongue or projection 10. In the normal position of the flap or shutter g , as shown in Figs. 1, 2, and 4, the same hangs by gravity 90 from its trunnions 9 and covers over the opening between the tongues e' of the fixed plate and the tongues f' of the chute. The chute, with the flap or shutter carried thereby, is substantially balanced in its pivotal 95 relation to the fixed plate e .

The parts are shown in Fig. 1 in their normal position, in which the end of the chute f closes off the coin-slot 5, so that no coin can be inserted below the rib 8. To insert a coin, 100 the rib 8 is depressed by the finger so as to open up the slot between the chute and the

plate, so that the coin can be passed through the coin-slot onto the chute, and as the chute occupies an inclined position the coin slides down the same, returning the chute to the 5 position Fig. 1 in its movements, passes between the series of tongues of the plate and the chute, and swings the flap or shutter *g* as it passes down into the receptacle, said flap or shutter returning to its position of 10 gravity, as shown in Fig. 1.

From this construction it will be apparent that if the chute is swung by pressure on the rib *S*, so as to insert any device for the extraction of a coin, the series of tongues will 15 interlock, as shown in Fig. 5, and close off the aperture between the plate and the chute, so that it will be impossible to insert a device for the extraction of a coin, and if it is 20 impossible to insert any device it is equally impossible for a coin to be extracted. If the parts are turned over in an effort to extract a coin, they will, by virtue of their balanced condition, assume the position Fig. 5, where the coin-slot is closed off from the receptacle, 25 but open between the chute and the plate; but it will be noticed that in this position the series of tongues are interlocked and the aperture between the plate and the chute is closed off. Furthermore, the flap or shutter, by virtue 30 of its overbalanced construction, is turned outward and over, so that the tongue of the flap or shutter bears against the outer surface of the plate in a tendency to keep the respective tongues in their interlocked position and 35 even insure the closing off of the parts, so as to effectually prevent the extraction of a coin. It will also be noticed from the construction that whether the parts are in the position Fig. 1 or in the position Fig. 5 the coin-slot 5 is at all times closed off to the receptacle and cannot be opened except to the space between the plate and chute.

I do not herein limit myself to the precise form or construction of the coin-receptacle 45 nor to the location of the door and lock at one end or to the character of the lock, as the same may be of any character affording a sufficient amount of security to the contents of the receptacle and of any suitable operative construction, my invention relating, 50 essentially, to the devices through which the coin is introduced into the receptacle.

I claim as my invention—

1. The combination with a coin-receptacle 55 having a coin-slot, of a plate fixed at one end to and within the coin-receptacle, and devices pivoted together and pivotally supported from said plate and substantially balanced in their movements and through which the 60 coin is passed.

2. The combination with a coin-receptacle having a coin-slot in one of the vertical portions, of a plate of rectangular form fixed at one end to and within the coin-receptacle and 65 directly over the coin-slot, and devices pivoted together and pivotally supported from the said plate and substantially balanced in

their movements and through which the coin is passed, said devices having a portion passing through the coin-slot and a portion normally covering the coin-slot in its relation to the receptacle. 70

3. The combination with a coin-receptacle, having a coin-slot in one of the vertical portions, of a plate of rectangular form having 75 one end bent at an obtuse angle and secured to the coin-receptacle so that the plate occupies an inclination, and a series of tongues formed at the other and free end of said plate, and trunnions upon the opposite sides of said plate, and devices pivoted together and pivotally supported from said plate and substantially balanced in their movements and through which the coin is passed. 80

4. The combination with a coin-receptacle 85 having a coin-slot in one of the vertical portions, of a plate of rectangular form having one end bent at an obtuse angle and secured to the coin-receptacle so that the plate occupies an inclination, a series of tongues formed 90 at the other and free end of said plate, and trunnions upon the opposite sides of said plate, devices pivoted together and pivotally supported from the trunnions of said fixed plate, and substantially balanced in their 95 movements and having a portion at one end normally closing the coin-slot with reference to the receptacle and an adjacent part passing through the coin-slot to be manually operated. 100

5. The combination with a coin-receptacle having a coin-slot in one of the vertical portions, of a plate of rectangular form having one end bent at an obtuse angle and secured to the coin-receptacle, so that the plate occupies an inclination, and a series of tongues formed at the other and free end of said plate, and trunnions upon the opposite sides of said plate, a chute comprising a bottom plate and sides embracing the fixed plate and having 105 apertures receiving the trunnions of said plate by which the chute is pivoted thereto, the bottom plate of said chute being turned up at one end to close off the coin-aperture and bent downward and outward as a rib projecting through the coin-slot to be manually operated, and a series of tongues in the other and inner end of said chute staggered with reference to the tongues of the fixed plate so as to interlock therewith, and a device pivoted 110 between the sides of the chute and adapted to normally close off the entrance from between the chute and the plate into the coin-receptacle. 115

6. The combination with a coin-receptacle 125 having a coin-slot in one of the vertical portions, of a plate of rectangular form having one end bent at an obtuse angle and secured to the coin-receptacle, so that the plate occupies an inclination, a series of tongues formed 130 at the other and free end of said plate, trunnions upon the opposite sides of said plate, a chute comprising a bottom plate and sides embracing the fixed plate and having aper-

tures receiving the trunnions of said plate by which the chute is pivoted thereto, the bottom plate of said chute being turned up at one end to close off the coin-aperture and bent downward and outward as a rib projecting through the coin-slot to be manually operated, a series of tongues in the other and inner end of said chute staggered with reference to the tongues of the fixed plate so as to interlock therewith, and a flap or shutter having trunnions on the opposite ends enter-

ing apertures in the sides of the chute at the inner end thereof, said flap or shutter hanging by gravity with its major portion below the trunnions and having at the other side a 15 central tongue.

Signed by me this 17th day of December, 1902.

AUG. GROSS.
